CYLINDER-GRIPPER AND SHOO-FLY ACTUATING MECHANISM

Joseph Sinkovitz and August A. Saul, Pittsburgh, Pa., assignors to Miller Printing Machinery Co., Pittsburgh, Pa., a corporation of Pennsylvania

Application April 1, 1937, Serial No. 134,344

12 Claims. (Cl. 101—409)

Our invention pertains to mechanism for actuating the cylinder grippers and the shoo-flies of cylinder printing presses, especially (though not necessarily) cylinder printing presses of the two-color type, employing two cylinders.

In presses of the character just mentioned, the impression cylinders normally occupy a depressed position in which the sheets thereon are contacted by printing forms carried by the type-bed. 10 But means are provided whereby either of the cylinders can be slightly raised when for some reason (such as the absence of a sheet thereon) it is not desirable that such cylinder occupy its normal depressed position. This raising of either 15 or both of the cylinders can be effected either automatically or manually by any one of a number of instrumentalities well known in the art.

Cylinder grippers retain the sheet on each cylinder during one of the two revolutions which the 20 cylinder makes for each cycle of the press, and must be opened, after such revolution, to permit the delivery of the sheet from the cylinder. Shoo-flies are also provided, for the purpose of raising the leading edge of the sheet from the 25 cylinder when the grippers are opened, thereby to facilitate delivery of the sheet. These shoo-flies are actuated after each printing revolution of the cylinder substantially coincidently with the opening of the grippers. A common mode 30 of thus opening the grippers and raising the shoo-flies is by means of what we may term a fixed cam (since it is fixed during the period of its actual operation) with which engage rollers associated with the gripper mechanism and the 35 shoo-fly mechanism, respectively, these mechanisms being carried by the rotating cylinder.

The fixed cam is designed and located, of course, for the most efficient operation when the cylinder is in its depressed, printing position. 40 When the cylinder is raised, even though the raising be slight, the rollers of the gripper and shoo-fly mechanism will not make their engagement with the fixed cam with entire precision and smoothness, with the result that, although the 45 grippers and shoo-flies will still perform their required functions, their operation will be noisy and accompanied by undue wear. This may be markedly detrimental,—particularly in the case of a two-color press. In such a press it frequently becomes desirable to print a single color. In that case the sheet would usually be printed on the first cylinder, then carried to the second cylinder by means of the usual transfer cylinder, and then allowed to travel round with the second cylinder, without any printing being done.

afterwards being delivered from the second cylinder. In this case the second cylinder would run continuously, throughout the printing of the whole job; and it is preferable that it run all the time in its raised position, though this has heretofore involved the disadvantage that has been mentioned.

With the foregoing in view, it is a main object of our invention to improve upon mechanisms for actuating the cylinder grippers and shoo-flies. 10 We attain this object by providing means whereby the grippers and shoo-flies are actuated with equal precision and smoothness regardless of whether the cylinder be in its normal or its raised position. Other objects of the invention will appear from the following specification and the 15 claims annexed thereto.

We have described, by way of example, in the following specification, and shown in the accompanying drawings, one form of actuating 20 mechanism in which our invention may be embodied. However, the invention may be embodied in other forms, and changes made in the particular form described and shown, without exceeding the scope thereof, as defined in the 25 appended claims.

In the drawings:

Fig. 1 is a partially diagrammatic view, with portions in section, of a two-color cylinder printing press showing part of the means for actuating 30 the cylinder-grippers and shoo-flies.

Fig. 2 is an end view of the second cylinder, the cylinder being shown as raised and in the position of rotation wherein the grippers are about to open and the shoo-flies to raise. In this view 35 a fixed cam, carried by the press-frame, is shown in section.

Fig. 3 is a view similar to Fig. 2 but with the cylinder shown as in its depressed, operating, position and in a position of rotation where the 40 grippers have just opened and the shoo-flies have raised.

Fig. 4 is a front view of the gripper-shaft lever and the coupling associated therewith.

Fig. 5 is an end view of the same, as seen from 45 the line V—V of Fig. 4.

Fig. 6 is a plan, as seen from the line VI—VI of Fig. 4.

Referring now to Fig. 1, *a* represents the first cylinder of a two-color press, to which the sheets 50 are fed from a feed-board or the like. In the normal operation of the press, the sheets are printed on the cylinder *a* and then forwarded, by a transfer cylinder *b*, to the second cylinder, designated *c*, where they are printed the second 55

time. The sheets are then delivered onto a suitable delivery apparatus, which may include stripper fingers *d*.

It will be sufficient to consider the second cylinder, *c*. This consists of substantially solid ends *10* and *11*, connected by a segmental printing portion *12* along one edge of which are arranged gripper pads *13*, all of well known construction. A shaft *14* rockably journaled between the ends *10* and *11* carries a plurality of spaced tumbler grippers *15* which cooperate with the pads *13*, to retain the sheet, in the usual way. From the gripper shaft *14* there extends an arm *16* upon which bears a spring device *17*, of common construction, which maintains the grippers *15* closed against their pads *13* except when the grippers are opened to receive a sheet (by well-known means not of importance here) or opened to deliver a sheet by the mechanisms hereinafter to be described.

Spaced along the cylinder, between the grippers *15*, are shoo-flies *18*. They are mounted on a shaft *19* and normally maintained in their depressed position (in which their tips lie beneath the edge of the sheet on the cylinder) by a spring *20*. An actuating arm *21* extends from the shaft *19* for engagement by a push rod *22* when the shoo-flies are to be actuated to raise them away from the cylinder.

In Figs. 2 and 3 there is shown the fixed cam, designated *e*, which performs the function of opening the grippers and raising the shoo-flies on the occasion of the delivery of the sheet from the cylinder. This cam is mounted on the printing press frame adjacent the end *11* of the cylinder, and, as is usual with such cams, is movable, axially of the cylinder, in such manner as to be in operative position during the second, or non-printing, rotation of the cylinder, but out of operative position during the first, or printing, rotation of the cylinder. Since we are here concerned with the non-printing rotation of the cylinder, during which the cam is in a stationary operative position, the cam *e* is appropriately referred to as a fixed cam.

For opening the grippers when the cylinder is in its raised position (Fig. 2), the cam *e* is formed with an extension *23* having a face *24* for engagement by a cam roll *25* carried by an arm *26* of a gripper-shaft lever *34*, rotatably mounted on the gripper shaft *14*. For opening the grippers when the cylinder is depressed (Fig. 3), the cam is formed with a face *27*, complementary to the face *24*, for engagement by a cam roll *28* carried by an arm *29* which extends from the gripper-shaft lever *34* in a direction opposite to the arm *26*. When the cam roll *25* engages the face *24*, the cam roll *28* clears the face *27*, and vice versa.

In order that the gripper-shaft lever, though rotatably mounted on the gripper shaft, may actuate the latter, the following provisions are made (Figs. 4-6). A coupling *35* is fixedly mounted on the gripper shaft adjacent the gripper-shaft lever, and is formed with a lug *36*. The gripper-shaft lever is formed with abutments *37* and *38* (which are relatively widely separated) for engagement by one side or the other of the lug *36* of the coupling. The gripper-shaft lever is further formed with an arm *39*, disposed in a plane axially beyond the abutments *37* and *38*, which is adapted to engage the flattened face of a pin *40* mounted in the cylinder-end *11*. The pin *40* is formed with an extension *41* for engage-

ment by the abutment *37* of the gripper-shaft lever.

In the normal position of the parts, the grippers are held closed, by the action of the spring *17*, and the lug *36* of the coupling is thus held in a leftward position in which it engages the abutment *37* of the gripper-shaft lever (Fig. 4). The locations of the pin *40* and of the arm *39* on the gripper shaft lever are such that, in these circumstances, the arm *39* will engage the pin. Thus the gripper-shaft lever is held in a position such that its cam rollers *25* and *28* will arrive at the cam *e* in correct relation with the cam-surfaces *24* and *27*. Whether the roller *25* be depressed by the cam-surface *24* or the roller *28* be raised by the cam-surface *27*, the effect will be the same. The abutment *37* on the gripper-shaft lever will be moved contra-clockwise, pressing against the lug *36* on the coupling *35* and moving it so as to rock the gripper shaft in a direction to open the grippers,—the arm *39*, of course, moving away from the pin *40*.

Suitable means are provided for rocking the gripper shaft by hand when it is desired to open the grippers for purposes of make-ready and the like. In that case the grippers are opened more widely than they are for the delivery of a sheet from the cylinder. When the delivery shaft is thus manually rocked nearly through the desired distance, the lug *36* of the coupling *35* comes into engagement with the abutment *38* of the gripper-shaft lever, whereafter such lever participates in the rocking movement. Thus the abutment *37* moves towards the extension *41* of the pin *40* until it engages such extension and prevents further rocking movement. At this time the grippers will have reached their fully open position. When the gripper shaft is manually rocked backward, to close the grippers, the parts will return to the normal position shown in Fig. 4.

One result of the foregoing construction, including the limiting of the possible positions of the gripper-shaft lever, is that if the grippers should mistakenly be left open when the press is started, or there should occur some other accident in operation such as would materially displace the gripper-shaft lever if it were fixedly secured to the gripper shaft, the gripper-shaft lever will nevertheless enter the race between the surfaces *24* and *27* of the cam *e*, so that no wreck would occur.

When the cylinder is raised, the roll *25*, in engaging the face *24*, causes the gripper shaft to be rocked contra-clockwise, whereby the grippers are opened, in the manner that has been described, against the action of the spring device *17*. When the cylinder is depressed, the roll *28*, in engaging the face *27*, likewise causes the gripper shaft to be rocked contra-clockwise, with a like result. Each of the cam-faces *24* and *27* can, of course, be formed with precision; so that the operation of opening the grippers is performed correctly and with smoothness, regardless of whether the cylinder is raised or depressed.

For raising the shoo-flies, the cam *e* is formed with a downwardly extending, approximately vertical leg *30* formed with a face *31* for engagement by a cam roll *32* carried by one arm of a bell-crank lever *33*. The other arm of the bell-crank lever is connected with the push-rod *22* described above. The configuration of the face *31* is such that when it is engaged by the roll *32*, the push-rod will be moved upward, to engage against the actuating arm *21* described above and thereby raise the shoo-flies.

Because of the approximately vertical disposition of the cam-face 31, substantially coinciding with the plane of movement of the cylinder in being raised or depressed, the difference in the actuating of the shoo-flies, occasioned by the raising of the cylinder, is so slight as to be negligible.

By our invention, therefore, we have provided a means for actuating the cylinder grippers and the shoo-flies of a cylinder printing press which will operate with equal precision and smoothness regardless of whether the cylinder occupies its raised or its depressed position. This is of material importance, and especially so where the cylinder is the second cylinder of a two-color press.

Having thus fully described our said invention, what we claim as new, and desire to secure by Letters Patent, is:

20 1. In a cylinder printing press, the combination with an impression cylinder, a printing member normally cooperating therewith, means for moving said cylinder into and out of cooperative relation with said printing member, and a cylinder gripper, of a cam for opening said gripper to permit delivery of a sheet, said cam having a surface for operation when said cylinder is in cooperative position with respect to said printing member and a second surface for operation when 30 said cylinder is out of cooperative position with respect to said printing member.

2. The combination with a press cylinder adapted to move toward and away from a bed reciprocating adjacent the cylinder, said cylinder having grippers carried on a common shaft journaled in the cylinder, of a lever on said shaft, and relatively fixed cam means for tilting said lever to rock said shaft, said means having a surface for tilting the lever when the cylinder is in 35 one position relative to the bed, and another surface for tilting the lever when the cylinder is in another position.

3. The combination with a press cylinder adapted to move toward and away from a bed reciprocating adjacent the cylinder, said cylinder having grippers carried on a common shaft journaled in the cylinder, of a lever on said shaft, and relatively fixed cam means for tilting said lever to rock said shaft, said means having a surface 40 for tilting the lever when the cylinder is in one position relative to the bed and another surface for tilting the lever when the cylinder is in another position, said surfaces being spaced apart radially of the cylinder.

4. The combination with a press cylinder adapted to move toward and away from a bed reciprocating adjacent the cylinder, said cylinder having grippers carried on a common shaft journaled in the cylinder, of a lever on said shaft, and relatively fixed cam means for tilting said lever to rock said shaft, said means having a surface for 45 tilting the lever when the cylinder is in one position relative to the bed and another surface for tilting the lever when the cylinder is in another position, said lever being rotatable on said shaft, and means whereby angular movement of the lever effects rotation of the shaft.

5. The combination with a press cylinder adapted to move toward and away from a bed reciprocating adjacent the cylinder, said cylinder having grippers carried on a common shaft journaled in the cylinder, of a lever on said shaft, and relatively fixed cam means for tilting said lever to rock said shaft, said means having a surface 50 for tilting the lever when the cylinder is in one

position relative to the bed and another surface for tilting the lever when the cylinder is in another position, said lever being rotatable on said shaft, and means secured to the shaft adapted to be actuated on angular movement of said lever. 5

6. The combination with a press cylinder adapted to move toward and away from a bed reciprocating adjacent the cylinder, said cylinder having grippers carried on a common shaft journaled in the cylinder, of a lever on said shaft 10 having arms extending in substantially opposite directions radially of the shaft, a relatively fixed interior cam adapted to cooperate with one end of the lever when the cylinder is in one position, and a relatively fixed exterior cam adapted to 15 cooperate with the other end of the lever when the cylinder is in another position.

7. The combination with a press cylinder adapted to move toward and away from a bed reciprocating adjacent the cylinder, said cylinder 20 having grippers carried on a common shaft journaled in the cylinder, of a lever on said shaft, relatively fixed cam means for tilting said lever to rock said shaft, said means having a surface for tilting the lever when the cylinder is in one position relative to the bed and another surface for tilting the lever when the cylinder is in another position, said lever being rotatable on said shaft, means secured to the shaft adapted to be actuated on angular movement of said lever, and 25 means for limiting rotation of said lever, the shaft being free for continued rotation after engagement of said limiting means by said lever.

8. The combination with a press cylinder adapted to move toward and away from a bed reciprocating adjacent the cylinder, said cylinder 30 having grippers carried on a common shaft journaled in the cylinder, of a lever on said shaft, relatively fixed cam means for tilting said lever to rock said shaft, said means having a surface 35 for tilting the lever when the cylinder is in one position relative to the bed and another surface for tilting the lever when the cylinder is in another position, said lever being rotatable on said shaft, means secured to the shaft adapted to be actuated on angular movement of said lever, means normally urging said shaft in one direction, and means limiting movement of the lever in the other direction whereby said lever is always 40 maintained in cooperative relation with said cam 45 means, said shaft being free for continued rotation after the lever has engaged said limiting means.

9. The combination with a press cylinder adapted to move toward and away from a bed reciprocating adjacent the cylinder, said cylinder 50 having grippers carried on a common shaft journaled in the cylinder, of a lever pivoted intermediate its ends on said shaft, relatively fixed cam means having separate surfaces adapted to 55 cooperate respectively with the ends of the lever when the cylinder is in different positions, a coupling secured to said shaft, and means whereby angular movement of the lever turns the coupling and shaft. 65

10. The combination with a press cylinder adapted to move toward and away from a type bed cooperating therewith, of shoo flies secured to a common shaft journaled in the cylinder, and means for actuating said shaft including a relatively fixed cam having a face extending in the general direction of movement of the cylinder whereby the rotation of said shaft caused by said cam is substantially the same regardless of the 70 position of the cylinder. 75

11. The combination with a press cylinder adapted to move toward and away from a type bed cooperating therewith, of shoo flies secured to a common shaft journaled in the cylinder, and 5 means for actuating said shaft including a relatively fixed cam, an actuating arm on said shaft, a push rod engaging said arm and lever adapted to engage said cam for actuating said rod, said lever being so spaced circumferentially of the cylinder 10 from said shaft that at the instant the lever engages the cam, the movement of the lever caused by the rotation of the cylinder is in substantially the same general direction as the movement of the cylinder toward and from the bed whereby the resulting operation of the shoo flies is substantially the same regardless of the 15 actual position of the cylinder relative to the bed.
12. The combination with a press cylinder adapted to move toward and away from a type bed cooperating therewith, of shoo flies secured to a common shaft journaled in the cylinder, means normally tending to turn said shaft in one direction but permitting manual rotation of the shaft in the other direction, and means for automatically rotating said shaft in said other direction on rotation of said cylinder including a relatively fixed cam having a face extending in the 10 general direction of movement of the cylinder whereby the rotation of said shaft caused by said cam is substantially the same regardless of the position of the cylinder. 15

JOSEPH SINKOVITZ.
